Fig. 7

Fig. 8

FIGURE 1 is a perspective view of a cooking stove or the like, in closed position, embodying our new design, a cabinet and counter top structure being included for illustrative purposes only;

FIGURE 2 is a side elevational view thereof;

FIGURE 3 is a perspective view thereof, in open position;

FIGURE 4 is a side elevational view thereof;

FIGURE 5 is a top plan view thereof, in closed position;

FIGURE 6 is a front elevational view thereof;

FIGURE 7 is a top plan view thereof, in open position; and,

FIGURE 8 is a front elevational view thereof.

The opposite side of the cooking stove not shown is like the side illustrated in the drawings.

The dominant features of the design reside in the portion shown in full lines.

We claim:

The ornamental design for a cooking stove or the like, as shown and described.
